MECHANICAL CATCHER FOR ROLLING MILLS

William John Crowley, Claymont, Del.

Application August 6, 1931. Serial No. 555,572

7 Claims. (Cl. 80—47)

This invention relates to certain improvements in mechanical catchers for returning the sheet bars from the pass between the rolls of a rolling mill to the front end of the mill by raising the sheet to a point over the upper roll and allowing it to be drawn over the upper roll and into position to again pass between the rolls in the reducing process.

The object of my invention is to so construct the apparatus that a carrier known as a peel will be held in a substantially horizontal position when it receives the sheet bar and then will be raised to the upper position, remaining substantially horizontal until it reaches a point above the upper roll of the mill so that the said bar can be pulled off of the peel and onto the table at the feed end of the mill, when it is again passed between the rolls and the above operation repeated.

In the accompanying drawings:

Fig. 1 is a side view of a two-high rolling mill, showing my improved mechanical catcher back of the rolls, and also showing the peel in full lines in the receiving position and in dotted lines in the upper position;

Fig. 2 is a sectional plan view on the line 2—2, Fig. 1;

Fig. 3 is a detached perspective view of the peel; and

Fig. 4 is a sectional view of one of the chains and a chain guide.

1 are the housings of the rolling mill. 2 is the lower roll and 3 is the upper roll. 4 is the feed table at the front of the rolls from which the sheet bar is fed to the pass between the rolls. 5 is a fixed rack at the rear of the rolls, onto which the sheet bar is delivered after it emerges from the pass between the rolls. This rack may be supported in a fixed position in any suitable manner.

6 is a base frame of my improved mechanical catcher. Mounted on one side of this frame is an electric motor 7, in the present instance. On the spindle 8 of this motor is a pinion 9, which meshes with the gear wheel 10 on a shaft 11, mounted in bearings 12. At the opposite end of the shaft 11 is a sprocket wheel 13 around which passes a chain 14. This chain passes around a sprocket wheel 15 on a shaft 16, which extends from one side of the frame to the other, as shown in Fig. 2. On this shaft is a sprocket wheel 16a, around which passes a chain 17, which in turn passes around a sprocket wheel 18, on a short shaft 19, having its bearings in the upper vertical bearing plate 20 at one side of the machine. On the shaft 19 is a sprocket wheel 21 for one of the

main chains 22, which carry the peel 23. This chain passes around a series of guide wheels 24—25—26 and partially around an offset guide wheel 27 and around sprocket wheels 28 and 29 at the upper end of the vertical bearing plate 20.

At the opposite side of the machine is a chain 30, which is driven from the shaft 16. On the end of the shaft 16 is a sprocket wheel 31, over which passes a chain 32 around a sprocket wheel 33 on a short shaft 34, on which is a sprocket wheel 35. The main chain 30 at that side of the machine passes around the sprocket wheel 35 and around guide wheels 36, 37 and 38, and partially around an offset guide wheel 39, and around sprocket wheels 40 and 41. The wheel 41 in the present instance is directly in line with the sprocket wheel 28 on the opposite side of the machine. The sprocket wheels 36 to 41, inclusive, are mounted on a bearing plate 20a. The two main chains 22 and 30 are driven at the same speed.

The peel 23 is made, in the present instance, as shown in Fig. 3, having a cross-bar 42. One end 43 of this bar is bent towards the rear and is secured to the chain 22 at "x". The other end 44 of the bar is bent forwardly and is attached to the chain 30 at "y". Projecting from the cross-bar 42 are a series of longitudinal bars 45, which are arranged to support the sheet bars as they are delivered from the pass of the rolls. The outer end of each bar 45 is tapered as at 46 to fit as close as possible the rolls 2 and 3 of the rolling mill.

By arranging the two main chains 22 and 30 in the manner shown and attaching the peel 23 to the chains as indicated in the drawings, the peel travels in a substantially horizontal path. For instance, when the peel 23 is in the position shown in full lines in Fig. 1, it is in position to receive a sheet bar as it is passed between the rolls 2 and 3 of the mill, and owing to the offsetting of the guide wheels 27 and 39 the peel is backed-off so as to clear the upper roll 3 while moving upwards and then is moved forward due to the position of the wheels 26, 28, 38 and 40, the peel being projected forwardly so as to be above the rolls and in position for an operator to grasp the sheet bar with tongs and to drop it onto the feed table at the front of the machine. The peel is then carried by the chains backwards to the extreme end of the machine and moved to the lower level and is brought forward to be again presented in position in front of the pass between the rolls to receive a sheet bar. This operation is continued until the bar has been reduced to the proper thickness.

It will be understood that in the drawings I have simply shown one peel but the machine may carry more than one peel if desired, without departing from the essential features of the invention. The chains are preferably guided by grooved rails shown as in Fig. 4 to prevent the chains from twisting, but other means may be provided if desired. It will be understood that the two main chains are driven in one direction only as indicated by the arrows in Fig. 1, and while I have shown the bearing frames 20 and 20a made of plates extending vertically from the base 6, the bearing frames may be designed in any suitable manner without departing from the essential features of the invention.

It will be understood that while I have described my invention as particularly adapted for handling plate bars, it can be used for handling sheet bars or other types of bars without departing from the essential features of the invention.

In the drawings a single chain is located at each side of the machine, but it will be understood that more than two chains may be used, and the chains may be arranged in sets if desired, depending upon the width of the rolls to which the mechanical catcher is applied.

I claim:—

1. The combination of a pair of rolls; a fixed rack which receives the plate bar from the pass between the rolls; two endless chains; means for driving the chains in the same direction; and a peel carried by the said chains in a substantially horizontal position, so as to lift the plate bar from the rack and deliver it to a point above the upper roll.

2. The combination in a rolling mill having two rolls; a rack at the rear of said rolls in position to receive a plate bar from the pass between the rolls; two endless chains moving in the same direction; means for driving said chains, one chain being located in advance of the other chain; and a peel secured to the two chains so as to remain in substantially a horizontal position, so that the peel will lift the plate bar from the rack and deliver it to a point above the upper roll.

3. The combination in a rolling mill, of two rolls; a rack at the back of the rolls and located so as to receive a plate bar from the pass between the rolls; two endless chains, one located in advance of the other and both driven in the same direction; means for driving said chains; three guide rollers at the front end of the machine, the central roll being offset; and a peel secured to both chains so that the peel after lifting the plate off of the rack will back away from the rolls to clear the upper roll and will be projected above the upper roll, the peel moving in a substantially horizontal plane.

4. The combination in a rolling mill, of two rolls; a rack back of the rolls, located to receive a sheet plate from the pass between the rolls, said rack consisting of a series of bars; two endless chains; sprocket wheels around which the chains pass; shafts for the said sprocket wheels;

bearings for the said shafts; means for driving the chains in one direction, the forward sprocket wheels being so arranged that the chains in passing from the lower to the upper run will be offset; a peel secured to both chains, said peel consisting of a transverse bar; and a series of longitudinal bars alternating with the bars of the rack, one of said chains being located in advance of the other, so that the peel will be held in the substantially horizontal position while it is lifting a plate bar from the rack to a point above the upper roll, the offsetting of the chains allowing the rack to clear the upper roll in its passage.

5. The combination in a rolling mill, of two rolls; a rack at the rear of the said rolls, in position to receive a plate bar from the pass between the rolls, said rack consisting of a series of longitudinal bars, disconnected at the rear end; a catcher consisting of a frame located at the rear of the rolling mill and having bearings for guide wheels; two chains arranged to pass around the guide wheels, one chain being on one side of the frame and the other on the opposite side thereof; and means for driving said chains, the forward end of one chain being located nearer the rolls than the forward end of the other chain; a peel consisting of a cross-bar and having longitudinal bars arranged to pass through the spaces between the bars of the rack, one end of the cross-bar having a rearward extension which is attached to the one chain, the other end of the bar having a forward extension attached to the other chain so as to retain the peel in a substantially horizontal position, said peel being arranged to lift a plate bar off of the rack and deliver it to a point above the upper roll.

6. The combination in a rolling mill having upper and lower rollers, of a rack at the rear of said rolls in position to receive a plate bar from the pass between the rolls, a plurality of endless chains arranged to move always in the same direction, means for driving said chains, at least one of the chains being located in advance of the rest and a peel secured to said chains so as to remain in a substantially horizontal position whereby said peel will lift a plate bar from the rack and deliver it to a point above the rolls, said peel being subsequently carried by the chains into position to lift another plate bar from said rack after the pass between said rolls.

7. The combination in a rolling mill having upper and lower rollers, of a rack at the rear of said rolls in position to receive a plate bar from the pass between the rolls, a plurality of endless chains arranged to move always in the same direction, means for driving said chains, and a peel secured to said chains so as to remain in a substantially horizontal position whereby said peel will lift a plate bar from the rack and deliver it to a point above the rolls, said peel being subsequently carried by the chains rearwardly of said rolls and then down and toward the rolls into position to lift another plate bar from said rack after the pass between said rolls.

WILLIAM JOHN CROWLEY. 140
